(57) **CLAIM**

I claim the ornamental design for a toy construction element, as shown and described.

DESCRIPTION

FIG. 1 is a perspective, top, front and right side view of the toy construction element showing an embodiment of the new design;

FIG. 2 is a top plan view of the toy construction element of FIG. 1;

FIG. 3 is a front elevation view of the toy construction element of FIG. 1;

FIG. 4 is a rear elevation view of the toy construction element of FIG. 1;

FIG. 5 is a right side elevation view of the toy construction element of FIG. 1;

FIG. 6 is a left side elevation view of the toy construction element of FIG. 1;

FIG. 7 is a bottom plan view of the toy construction element of FIG. 1; and,

FIG. 8 is a perspective, bottom, back and right side view of the toy construction element of FIG. 1.
